(57) **CLAIM**

The ornamental design for a dental camera, as shown and described.

DESCRIPTION

FIG. 1 illustrates a perspective view of a dental camera showing our new and ornamental design;

FIG. 2 illustrates a left side elevation view thereof;

FIG. 3 illustrates a right side elevation view thereof;

FIG. 4 illustrates a bottom plan view thereof;

FIG. 5 illustrates a top plan view thereof;

FIG. 6. Illustrates back elevation view thereof; and,

FIG. 7 illustrates a front elevation view thereof.

The broken lines are included for the purpose of illustrating portions of the dental camera that form no part of the claimed design.
